UNITED STATES PATENT OFFICE.

IRVING L. BRIGGS, OF NEWPORT, DELAWARE.

MECHANICAL CHARGING MECHANISM FOR SMELTING-FURNACES AND THE LIKE.

1,022,654.

Specification of Letters Patent.

Patented Apr. 9, 1912.

Application filed November 13, 1911. Serial No. 559,972.

To all whom it may concern:

Be it known that I, IRVING L. BRIGGS, a citizen of the United States, residing at Newport, in the county of Newcastle and State of Delaware, have invented certain new and useful Improvements in Mechanical Charging Mechanism for Smelting-Furnaces and the Like, of which the following is a specification.

10 My invention relates to improvements in mechanical charging mechanism for smelting furnaces and the like, the object of the invention being to provide an improved apparatus which will simultaneously charge 15 a plurality of superimposed retorts, and which may be moved from one column or tier of retorts to the next as desired.

A further object is to provide an improved apparatus of the character stated 20 which is especially adapted for use in connection with a smelting furnace having a longitudinal series of tiers of retorts, and which is adapted to be moved along in front of the furnace, and which is adapted to be 25 moved toward and away from the furnace, so as to position its discharge nozzles into the retorts, and move out of the retorts when the device is to move from one tier of the retorts to another.

30 A further object is to provide an apparatus of this character in which any of the feeding mechanism may be stopped, and in which the control of the device is simple and easily managed by an operator.

35 With these and other objects in view, the invention consists in certain novel features of construction and combinations and arrangements of parts, as will be more fully hereinafter described and pointed out in the 40 claims.

In the accompanying drawings: Figure 1, is a view in vertical section through a smelting furnace illustrating my improved apparatus in elevation in position to charge 45 the retorts. Fig. 2 is a view in elevation of my improved apparatus taken at right angles to Fig. 1. Fig. 3, is a sectional view on an enlarged scale illustrating the conveyer driving mechanism, the mounting for 50 one of the idle sprocket wheels, and a portion of one of the conveyers. Fig. 4, is a view in horizontal section, and Fig. 5, is an

enlarged detail view partly in section and partly in elevation illustrating the clutch 16, and the pinions which it controls. 55

1, represents a smelting furnace which is provided with a plurality of vertical tiers of retorts 2. The exact arrangement of the retorts and the construction of the furnace are, of course, immaterial to this invention, 60 but my construction is adapted for use in connection with a furnace which has a plurality of vertical tiers of retorts, and is adapted to simultaneously charge all of the retorts in any vertical tier, and to be moved 65 from tier to tier.

3, represents the rails of the track which extends along the furnace 1, and on which the wheels 4 of a car 5 are mounted to run. The wheels 4 are fixed to their axles 6, 70 and one of the axles is provided with a worm wheel 7 driven by a worm 8 on a shaft 9. The worm wheel 7 and the worm 8 communicate through an opening 10 in the car platform 5, as it is to be understood that 75 the car itself consists of a horizontal platform and the axles and wheels above referred to, hence the part 5 is referred to indiscriminately as a platform and a car.

A motor 11 is provided on the platform 5, 80 and drives a transversely positioned shaft 12. On this shaft 12, two facing beveled gears 13 and 14 respectively are loosely mounted, and both mesh with a beveled gear 15 secured to the shaft 9. A clutch 16 keyed 85 to the shaft 12 is mounted between pulleys 13 and 14, and is adapted to be moved into locked engagement with either or to an idle position between them. By means of this clutch 16, the direction of movement of 90 the shaft 9 and the car, may be changed, so that the car may be moved along the track 3 in either direction, and may be stopped when the clutch assumes an idle position between the gears. When so stopped, the 95 worm 8 will prevent accidental movement of the car on its track. This clutch 16 may be operated in various ways, a lever 17 being supported in the grooved, central portion of said clutch, and will answer the 100 purpose.

On the platform 5, the rails 18 of a transversely positioned track 19 are secured, and support the wheels 20. These wheels 20 are

fixed to axles 21 which have bearings in bars 22, and said bars are secured to the bottom of a receptacle 23, which latter is provided at its upper end with an enlarged 5 hopper 24 to maintain the receptacle full of the charge for the furnace. On the bottom of receptacle 23, a transversely positioned horizontal rack bar 25 is secured, and with which a pinion 26 meshes. This pinion 26 10 is fixed to a longitudinally extending shaft 27 provided at one end with a beveled gear 28. This gear 28 meshes with facing beveled gears 29 and 30 loose on shaft 12, and adapted to be locked to said shaft by a clutch 31, 15 which is keyed to the shaft and located between the gears 29 and 30. This clutch is adapted to lock either of the gears 29 and 30 to the shaft 13, so as to drive shaft 27 in either direction, and is also adapted to assume an idle position between them. A 20 lever 32 is provided for moving the clutch, so that the operator may, by means of the clutch, move the receptacle toward and away from the furnace as will be readily understood.

Two parallel vertical series of discharge tubes 33 extend through the inner vertical wall of receptacle 23, are flared outward at their inner ends as shown at 34, and are 30 supported in rings 35 fixed to the receptacle 23 around the openings through which said tubes project. These tubes are also supported by coupled rings 36 which are connected to sectional rods 37 secured to the 35 hopper 24, and have turn buckles 38 so as to adjust the length of said rods and determine the adjustment of said supporting rings. On the free ends of these tubes 33, slightly conical and movable nozzles 39 are 40 provided, and are adapted to be projected through the twyer openings 40 in the retorts 2. As the retorts are commonly provided with two twyer openings, my apparatus is provided with two tubes for each 45 retort, and these tubes are arranged in vertical series as above explained, so that they may simultaneously feed into all of the retorts of a vertical tier.

In each of the tubes 33, worm conveyers 50 41 are located, and extend into the receptacle 23, so that the charge is fed outwardly through the tubes 30 by means of the rotary movement of the worm conveyers. The shafts 42 of these worm conveyers extend through 55 the outer wall of receptacle 23, and they are all provided with sprocket wheels 43 which are loose on the shafts 42. The hub of one of these sprocket wheels 43 has fixed thereto a second sprocket wheel 44 which is connected by a chain 45 with a sprocket wheel 46 on a motor shaft 12. Clutches 47 keyed to the shafts 42 are provided, and are adapted to lock the sprocket wheels to the shafts. Levers 48 fulcrumed at their inner ends on

posts 49, engage said clutches and are adapted to move them so that while all of the shafts are normally operated at the same time, a condition may arise where it is desirable to stop one or more of the worm conveyers, and these clutches or levers permit this to be done.

The sprocket wheels 43 are all driven by a single sprocket chain 50, which is held in close contact with the sprocket wheels 43 by means of idle sprocket wheels 51. These 75 idlers 51 are mounted on blocks 52 which slide in channel bars 53, and are adjustable therein by means of set screws 54, so that the said idle sprockets may be adjusted to take up all slack in the chain, and insure a 80 perfect engagement of the chain with the sprocket wheels 43, and therefore insure a perfect drive of the conveyers.

It will be noted that by the employment of my improved apparatus, I am enabled to 85 mechanically feed crushed ore or other charge into a retort or retorts; preferably a vertical tier of retorts, and move the apparatus from one retort or tier of retorts to another throughout the furnace. The 90 charge, of course, may be supplied in any way, preferably from above into the hopper, and the retorts may be quickly and uniformly charged.

While I have shown what I believe to be 95 a preferred arrangement of power transmitting mechanism, together with clutches and other means for controlling the transmissions of the power, I would have it understood that I do not limit myself to the precise details set forth, but consider myself at liberty to make such changes and alterations as fairly fall within the spirit and scope of the appended claims.

Having thus described my invention, 105 what I claim as new and desire to secure by Letters Patent is:

1. An apparatus of the character described, comprising a car, a receptacle movable transversely of the car, a tube communicating with the receptacle and adapted to direct contents of said receptacle into a furnace, a movable nozzle on the outer end of the tube, and means for forcing the material through said tube, substantially as described.

2. An apparatus of the character described, comprising a car, a receptacle on the car, means for moving the receptacle transversely of the car, a vertical series of 120 tubes communicating with the receptacle, and means for forcing material from said receptacle through said tubes, substantially as described.

3. An apparatus of the character described, comprising a car, a receptacle on the car, means for moving the receptacle transversely of the car, a vertical series of

tubes communicating with the receptacle, and worm conveyers in said tubes extending into the receptacle and adapted to force the material from the receptacle through said tubes, substantially as described.

4. An apparatus of the character described, comprising a car, a receptacle on the car, means for moving the receptacle transversely of the car, a vertical series of tubes communicating with the receptacle, worm conveyers in said tubes extending into the receptacle and adapted to force the material from the receptacle through said tubes, the inner ends of said tubes projecting into the receptacle and flared outwardly, substantially as described.

5. An apparatus of the character described, comprising a car, a receptacle on the car, means for moving the receptacle transversely of the car, a vertical series of tubes communicating with the receptacle, worm conveyers in said tubes extending into the receptacle and adapted to force the material from the receptacle through said tubes, movable nozzles on the free ends of said tubes, and means for simultaneously turning all of said conveyers, substantially as described.

6. An apparatus of the character described, comprising a car, a receptacle on the car, means for moving the receptacle transversely of the car, a vertical series of tubes communicating with the receptacle, worm conveyers in said tubes extending into the receptacle and adapted to force the material from the receptacle through said tubes, the inner ends of said tubes projecting into the receptacle and flared outwardly, movable nozzles on the free ends of said tubes, and means for simultaneously turning all of said conveyers, substantially as described.

7. An apparatus of the character described, comprising a car, wheels supporting the car, a motor on said car adapted to turn the wheels, a transversely positioned track on said car, a receptacle, wheels on said receptacle mounted to run on the said track, means operated by the motor for turning the said wheels to move the receptacle transversely of the car, a vertical series of horizontally positioned tubes communicating with the receptacle, conveyers in said tubes, shafts fixed to said conveyers and projecting through the receptacle, and means for transmitting motion from the motor to said shafts, substantially as described.

8. An apparatus of the character described, comprising a car, wheels supporting the car, a motor on said car adapted to turn the wheels, a transversely positioned track on said car, a receptacle, wheels on said receptacle mounted to run on the said track, means operated by the motor for turning the said wheels to move the receptacle transversely of the car, a vertical series of hori-

zontally positioned tubes communicating with the receptacle, conveyers in said tubes, shafts fixed to said conveyers and projecting through the receptacle, sprocket wheels loose on said shafts, clutches adapted to lock said sprocket wheels to the shafts, means for moving the clutches, a sprocket chain connecting all of said sprocket wheels, and means for transmitting motion from said motor to one of said sprocket wheels, substantially as described.

9. An apparatus of the character described, comprising a car, wheels supporting the car, a motor on said car adapted to turn the wheels, a transversely positioned track on said car, a receptacle, wheels on said receptacle mounted to run on the said track, means operated by the motor for turning the said wheels to move the receptacle transversely of the car, a vertical series of horizontally positioned tubes communicating with the receptacle, conveyers in said tubes, shafts fixed to said conveyers and projecting through the receptacle, sprocket wheels loose on said shafts, clutches adapted to lock said sprocket wheels to the shafts, means for moving the clutches, a sprocket chain connecting all of said sprocket wheels, transversely positioned guides between the shafts, blocks mounted to move in said guides, screws engaging said blocks, and idle sprocket wheels on said blocks engaging the sprocket chain and pressing the same inwardly between the first-mentioned sprocket wheels, substantially as described.

10. In an apparatus of the character described, the combination with a car platform, axles supporting the car platform, and wheels fixed to said axles, of a worm wheel on one of said axles, a motor on the car platform, a worm engaging said worm wheel, a shaft fixed to said worm, a pinion on one end of said shaft, a motor shaft, two pinions loose on the motor shaft meshing with the first-mentioned pinion, a clutch on the motor shaft adapted to lock either of said motor shaft pinions to the shaft or lie idly between them, a receptacle, wheels supporting said receptacle, a transversely positioned track on said platform on which said wheels are mounted, a rack bar on the lower end of said receptacle, a pinion engaging said rack bar, means for transmitting motion from said motor shaft to said last-mentioned pinion to turn the latter in either direction, tubes communicating with said receptacle and adapted to feed material into a furnace, and conveyers in said tubes, substantially as described.

11. An apparatus of the character described, comprising a car, a receptacle movable transversely of the car, a motor, means operated by the motor for moving the car and for moving the receptacle, two vertical

41
series of horizontally positioned tubes communicating with the said receptacle, conveyers in said tubes, means for simultaneously operating all of said conveyers, collars 5 on said tubes coupled together, and adjustable rods connecting the upper collars with the receptacle, substantially as described.

In testimony whereof I have signed my name to this specification in the presence of two subscribing witnesses.
